EX

OR D 11,550

No. 11,550

DEC 23, 1879

UNITED STATES PATENT OFFICE.

HENRY K. WHITE, OF MERIDEN, CONNECTICUT, ASSIGNOR TO THE WILCOX
& WHITE ORGAN COMPANY, OF SAME PLACE.

DESIGN FOR AN ORGAN-CASE.

Specification forming part of Design No. **11,550**, dated December 23, 1879; application filed October 15, 1879.
[Term of patent 7 years.]

To all whom it may concern:

Be it known that I, HENRY K. WHITE, of Meriden, in the county of New Haven and State of Connecticut, have invented a new Design for Organ-Case; and I do hereby declare the following, when taken in connection with the accompanying illustration and the letters of reference marked thereon, to be a full, clear, and exact description of the same, and which said illustration constitutes part of this specification, and represents a perspective view.

This invention relates to a design for case for reed-organs and similar instruments; and it consists in the shape or configuration of the parts, as shown in the accompanying illustration.

The main body of the case is of usual form, with the key-section projecting in front. The ends of the key-section are inclined from the front back and upward to the body of the case, and supported from below by a scroll-shaped truss at each side. The ends extend up, and a gallery runs across from end to end. On the ends is a raised panel, *a*, extending from the base up to the key-section, with a molding across at that point, and crowned with scroll-work above said molding. At each end of the key-section a bracket, *b*, projects, each

supporting a shelf. Above the gallery the center of the back is carried up and crowned with a semicircular molding, and with scroll-work at each side; and from the face of this, at each side, brackets *d* extend outward, supporting inclined shelves or pockets, all as shown in the accompanying illustration.

I claim—

1. The design for an organ-case, consisting of the raised panel *a*, extending from the base upward, with molding across the top, and crowned with scroll-work, as described and shown.

2. The design for an organ-case, consisting of the outwardly-projecting bracket *b* at each end of the key-section, and a shelf on each bracket in the plane of the molding across the top of the end panels, as described and shown.

3. The design for organ-case, consisting of the central upward extension of the back, with scroll-work at each side, and brackets projecting from the face, and inclined shelves between said brackets, all as described, and shown in the accompanying illustration.

HENRY K. WHITE.
